BALL MILL AND VAPOR CONDENSER

Lincoln M. Shafer, Upper Montclair, N. J.

Application November 19, 1947, Serial No. 786,915

4 Claims. (Cl. 241—101)

1

This invention relates to novel apparatus and more particularly to novel apparatus including a ball mill reactor. In one of its more specific aspects the invention is directed to novel apparatus of the aforesaid type operating under reduced pressure conditions.

An embodiment of the apparatus and method of operating the same will hereinafter be described in conjunction with the apparatus shown in the drawings, wherein:

Fig. 1 is a view partly in section and partly in side elevation of an illustrative embodiment of the invention.

Fig. 2 is a fragmentary view in elevation and section of a modification of the apparatus shown in Fig. 1.

As shown in the drawings there is provided a ball mill 10 having a rotatable chamber 11 in which are located a plurality of steel or other type of crushing balls 12 or the like. One side 13 of the chamber 11 has a large diameter gear 14 fixedly secured thereto and driven by a small drive gear 15 keyed to a drive shaft 16 of a driver 17 which may be an electric motor or any other convenient driving mechanism. Keyed to the gear 14 and extending outwardly therefrom is one end of a supporting shaft 18 having its other end journaled in a bearing 19 carried by a vertical support 20. Disposed below the chamber 11 is a source of heat which may be a burner 21 such as a gas burner or the like.

The chamber 10 has an inlet opening sealed by a demountable cover plate (not shown) and an outlet opening. A hollow shaft 22 is secured to the other side 23 of chamber 11, extends outwardly therefrom and communicates with the interior of chamber 11. A condensing or catch chamber 25 has an opening in one side thereof in which extends one end of the hollow shaft and outlet 22. Mounted on the shaft 22 near that portion of chamber 25 in which said shaft extends is a packing ring, piston or other device 26 for maintaining an air seal therebetween. A stationary collar 27 is mounted on shaft 22, has an annular opening in which is disposed the air sealer 26 and is secured to the stationary chamber 25 by stud bolts 28. The collar 27 is journaled in a bearing 29 mounted on a support 30. The receiving chamber 25 has an opening in the other side thereof communicating with the opening through a hollow member 31 extending outwardly therefrom and in alignment with the hollow shaft 22. A collapsible element 32 such as a bellows or the like composed of any suitable gas impervious material has one end thereof air sealed to the

2

outer end of the element 31 and its other end is air sealed to one end of a reciprocable head 33 having an opening 34 therein accommodating one end of a suction or vacuum hose 35 having its other end connected to a vacuum pump (not shown). Integral with the head 33 and extending inwardly therefrom is a breaking or reaming rod 36 passing through the member 31. The receiving chamber 25 may have a water cooling jacket 37. The diameter of rod 36 is slightly less than the internal diameter of supports 22 and 31. The head 33 is pivotally connected to one end of a link 38 which has its other end pivotally connected to an eccentric 39 mounted on support 40 and driven by a motor 41.

In operation, the motor 41 is energized to drive the ball mill chamber 11 in which is located a composition which with or without the aid of heat vaporizes, while under reduced pressure conditions due to the vacuum therein by operation of a vacuum pump connected thereto through the hose 35, bellows 31, chamber 25 and conduit 26 being a vacuum line to chamber 11. The vacuum or reduced pressure conditions is constantly maintained by the pump. The vaporized material may be a reaction product or a distillation product of a reaction product produced in situ. The vaporized material passes out of the chamber 11 through the rotating outlet 22 and into the chamber 25 in which it is received and condensed and the condensate may be tapped therefrom through outlet 42. To prevent plugging of outlet 22 by the vaporized material which may deposit and solidify therein, the head 33 is reciprocated by the eccentric 39 to reciprocate the rod 36. Reciprocation of rod 36 forces the rod 36 through the entire length of outlet 22 and then retracts the rod 36 entirely outside of outlet 22. In the embodiment of the invention shown in Fig. 1 the collapsible bellows 32 permits reciprocation of the bellows while the reduced pressure conditions are maintained in chamber 11 without impairment of the vacuum line. Instead of the bellows with the reciprocating head, I may reciprocate a free rod by means of an electro-magnetic arrangement.

I claim:

1. The combination of a rotatable ball mill chamber having an opening in one side thereof, a stationary receiving chamber, a hollow conduit, said chambers communicating with each other through said conduit for the passage of vaporized material from said ball mill chamber to said receiving chamber, a vacuum line for maintaining sub-atmospheric pressure conditions in said ball mill chamber, a rod located in said line and means

for reciprocating said rod in said conduit to remove therefrom said material which has deposited therein without impairing the maintenance of said sub-atmospheric pressure conditions in said chamber.

2. The combination of a rotatable ball mill chamber having an opening in one side thereof, a hollow conduit coupled with said chamber at said opening and rotatable therewith for the passage of vaporized material from said ball mill chamber and through said conduit, a stationary receiving chamber, said receiving chamber also coupled with said hollow conduit at one side thereof to receive said material from said conduit, the other side of said chamber having an opening therein, a vacuum line coupled with said chamber at said opening, a rod located in said vacuum line and means for reciprocating said rod in said conduit without impairing the maintenance of said sub-atmospheric pressure conditions in said chamber.

3. The combination of a rotatable ball mill chamber having an opening in one side thereof, a stationary receiving chamber, a hollow conduit communicating with said chambers for the passage of vaporized material from said ball mill chamber to said receiving chamber, a bellows communicating with said receiving chamber, a rod carried by said bellows and a vacuum pipe operatively connected to said bellows, said bellows being operative to reciprocate said rod in said conduit to remove therefrom said material deposited therein without impairing the maintenance of sub-atmospheric pressure conditions in said chamber.

4. The combination of a rotatable ball mill chamber having an opening in one side thereof, a stationary receiving chamber, a hollow conduit communicating with said chambers for the passage of vaporized material from said ball mill chamber to said receiving chamber, a bellows communicating with said receiving chamber, a rod carried by said bellows and a vacuum pipe operatively connected to said bellows, and means for actuating said bellows to reciprocate said rod in said conduit, said bellows being operative to reciprocate said rod in said conduit to remove therefrom said material deposited therein without impairing the maintenance of sub-atmospheric pressure conditions in said chamber.
